UNITED STATES PATENT OFFICE.

OSCAR ROESEN, OF NEW YORK, N. Y., ASSIGNOR TO ROBERT HOE, OF NEW YORK, N. Y.

DEVICE FOR PREVENTING SMEARING.

SPECIFICATION forming part of Letters Patent No. 746,746, dated December 15, 1903.

Application filed June 1, 1901. Serial No. 62,729. (No model.)

To all whom it may concern:

Be it known that I, OSCAR ROESEN, a citizen of the United States, residing at New York, county of New York, and State of New York, have invented certain new and useful Improvements in Devices for Preventing Smearing, fully described and represented in the following specification and the accompanying drawings, forming a part of the same.

10 This invention relates to certain improvements in devices for preventing offset and smearing in printing-machines.

In printing-machines, and more especially in machines which print upon webs, stationary guides are employed for the purpose of supporting the traveling web and for giving it direction. When a traveling web which has been freshly printed passes over such a stationary guide, it is liable to become 20 smeared, especially where, as in many instances, the web carries heavily-printed cuts. The difficulty referred to frequently occurs in forwarding webs where the webs are caused to pass around angle or turner bars for the 25 purpose of changing the direction of movement. In such cases the web is strained around the bar, and its freshly-painted surface, especially where this surface, as has been before stated, is composed in whole or 30 in part of heavily-inked cuts, is apt to become rubbed or smeared, and, furthermore, any ink which is rubbed off onto the bar will set off onto the succeeding portions of the web.

35 The invention has for its object to produce an improved means whereby webs may be led over stationary guides without becoming smeared or without liability of offset.

With this and other objects in view the 40 invention consists in certain constructions and in certain parts, improvements, and combinations, as will be hereinafter fully described and then specifically pointed out in the claims hereunto appended.

45 In the accompanying drawings, in which like characters of reference indicate the same parts, Figure 1 is a plan view of so much of a printing-machine as is necessary to illustrate the invention. Fig. 2 is a side view of 50 the construction shown in Fig. 1, certain parts being broken away and certain parts

being shown in section, the view being taken in the direction indicated by the arrow 2 in Fig. 1. Fig. 3 is a front view of the construction shown in Fig. 1, the view being taken in the direction of the arrow 3 in that figure. Figs. 4 and 5 are detail sectional views illustrating a modified construction.

Referring to the drawings, 1 indicates portions of the side frames of a printing-machine, 60 which frame may be of any approved construction. These side frames are connected by cross-webs or brace-bars 2 and 3. In the present machine the printed product consists of a perfected double wide web the columns 65 of which are at right angles to the general direction of movement of the web. This web may be printed upon by printing-couples of any approved type; but since the construction of these couples has no relation to 70 the present invention they are not shown. The web after leaving the printing-couples is led over a guide 4, which is or may be a compensating roll of the usual type. After leaving the compensating roll the web passes 75 over a slitting-roll 5, where it is divided into two sections A and B by means of a slitter 6 of any ordinary construction. After leaving the slitting-roll the portion A of the web is led forward and over a stationary 80 guide 7, which in the present instance is a turner-bar, by which the web is given a direction at right angles to the line of movement it had when it left the slitter. The portion B of the web after leaving the slitter 85 is led under a roll 8 and then forward to a stationary guide 9, which in the present instance is a turner-bar, by which the direction of the web is changed, so that it runs beneath the portion A in order that it may 90 be associated therewith. The portion A of the web is led over a suitable guide-roll 10 to a cutting and folding mechanism 11, and the portion B is led over a roll 12 to the same cutting and folding mechanism, the two portions being associated by this mechanism.

In order to prevent smearing and offsetting as the web passes over the guides 7 and 9, which, as before stated, are turner-bars, a moving shield is employed. This moving 100 shield may be constructed and operated in various ways. In the preferred form of the

construction the shield consists of a belt, which may be formed of any suitable material, said shield passing between the stationary web-guides and the traveling web and being caused to move at a rate of speed substantially equal to the speed of the web. While an independent shield might be provided for each web-guide, in the preferred form of the construction the belt which forms the shield will be endless, a single belt being utilized to form the shield for both guides.

The belt which forms the shield may be arranged and driven in any suitable manner. In the construction shown, however, the belt 13, which forms the shield and which is substantially equal in width to the printed matter on one of the sections A B, meets the web as the web passes over the slitting-roll 5, said belt passing between the slitting-roll and the web. After leaving the slitting-roll the belt runs forward beneath the web and passes around the guide 7 and between said guide and the web. After leaving the guide 7 the belt passes over angle-bars 14 15, which change its direction, as clearly indicated in Fig. 1. After leaving the angle-bar 15 the belt passes over and around a roll 16 and between this roll and a roll 17. After leaving the roll 17 it passes onward to a guide 18, which is located over the section B of the web and which changes the direction of movement of the belt, as clearly indicated in Fig. 1. After leaving the guide 18 the belt passes onward and around the guide 9, being interposed between this guide and the section B of the web. The belt follows the run of this section until both reach the roll 12, before referred to as the roll over which this section passes to the cutting and folding mechanism, after which the belt takes a turn backward around the roll 12 and passes over a turner-bar 19. This turner-bar 19 is located in the construction shown under the bar 7 and operates to turn the belt so that it runs back to a roll 20, which is preferably a driven roll, as will hereinafter appear.

The slitting-roll 5 will preferably be driven as is usual. The means by which this roll is driven may be of any preferred type. As shown, a gear 21 is provided, which is mounted on a suitable stud on one of the side frame-pieces and which is driven from any suitable moving part of the machine by any suitable train of gears or other connections. This gear 21 meshes with an intermediate 22, also mounted on the frame of the machine, and this intermediate is in mesh with a small gear 23, which is mounted on the shaft 8' of the roll 8, this gear being also located on the outside of the frame. The shaft 8' is provided on the inside of the frame with a gear 24, which meshes with a gear 25 on the shaft 5' of the slitter-roll.

The shield may be driven by any suitable arrangement of driving mechanism. As shown, the rolls 16 and 17, over and between which the belt passes, are driven rolls. While the

movement of these rolls may be derived from any suitable moving part of the machine, as shown, the shaft 8' is provided with a bevel-gear 26, which meshes with a similar gear 27 on a short shaft 28, journaled in the cross-brace 2, before referred to. The other end of this short shaft 28 carries a gear 29, which meshes with a gear 30 on the shaft of the roll 17, said shaft having its bearings in cross-braces 2 and 3. The shaft of the roll 16 is provided with a gear 31, which meshes with the gear 30, said shaft also finding its bearings in the cross-braces 2 and 3.

While the rolls 16 and 17 may be depended upon to give the belt its movement, in the construction shown the shaft which carries the roll 20, before referred to, is also preferably provided with a gear 33, said gear meshing with an intermediate 34, which is driven from the gear 25 on the shaft 5'.

Inasmuch as the belt which forms the shield travels when in contact with the printed web at the same rate as the web, there is little liability of offset; but should some ink be set off onto the belt it will have an opportunity to dry between the times when the belt leaves the first portion of the web and comes in contact with the second portion.

In the construction shown in the figures so far described the belt has a plain surface, so that its entire surface may come in contact with the paper. If desired, however, ribs, which may be in the form of tapes 35, (see Figs. 4 and 5,) may be formed on the belt, so that the major portion of the belt will not come in contact with the web.

While the construction which has been described forms a preferred embodiment of the invention, it is to be understood that the invention is not to be confined thereto, but that various changes and modifications may be made therein without departing therefrom.

What is claimed is—

1. The combination with an angle-bar forming a stationary web-guide which changes the direction of movement of the web, of a shield interposed between the web and the guide, and means for driving the shield, substantially as described.

2. The combination with a plurality of angle-bars forming guides for a web or webs, of an endless belt passing around the bars, said belt being interposed between the web and the bars and forming a shield, and means for driving the belt, substantially as described.

3. The combination with a slitting mechanism, of angle-bars for guiding parts of the slit web, an endless traveling belt forming a shield and passing between the bars and the web, means for supporting and guiding the belt, driving-rolls for the belt, and means for operating the rolls, substantially as described.

4. The combination with means for forwarding a plurality of webs, of angle-bars for changing the direction of movement of the webs, an endless belt forming a shield pass-

ing around the bars and between the bars and the webs, guides for controlling the movement of the belt, and driven rolls around which the belt passes, substantially as described.

5. The combination with a stationary web-guide, of a shield interposed between the web and the guide, said shield consisting of a belt having a plurality of ribs on its operating-surface, and means for driving the shield, substantially as described.

6. The combination with a stationary web-guide, of a shield interposed between the web and the guide, said shield consisting of an endless belt having a plurality of ribs on its operating-surface, and means for driving the shield, substantially as described.

7. The combination with an angle-bar, arranged to form a guide for a web or webs, of an endless belt passing around the bar and

between the bar and the web or webs, said belt having a plurality of ribs on its operating-surface, and means for driving the belt, substantially as described.

8. The combination with means for forwarding a plurality of webs, of angle-bars for changing the direction of movement of the webs, a pair of driven rolls, an endless belt driven by the rolls, said belt passing between the angle-bars and the webs, and a plurality of guides, said guides including suitably-arranged angle-bars for controlling the movement of the belt, substantially as described.

In testimony whereof I have hereunto set my hand in the presence of two subscribing witnesses.

OSCAR ROESEN.
